UNITED STATES PATENT OFFICE.

WALTER K. VOORHEES, OF CEDAR FALLS, IOWA, ASSIGNOR TO STANDARD MANUFACTURING COMPANY, OF CEDAR FALLS, IOWA.

ADJUSTABLE STREET SIGN.

Application filed August 9, 1926. Serial No. 128,100.

My invention relates to improvements in adjustable street signs, and the object of my improvement is to furnish a plurality of signs to be supported at the intersection of two or more streets, the signs being adjustably mounted in superposition for relative adjustments to place them respectively parallel with a street for which the particular sign is an indicator, and then secured separately in the desired adjustment, the means for adjustment being such as to permit of unlimited rotational adjustment of one sign upon another and to prevent longitudinal displacements or sidewise tilting of a supported sign.

This object I have accomplished by the means which are hereinafter described and claimed, and which are illustrated in the accompanying drawings, in which Fig. 1 is an elevation of superposed street signs as connected and secured together in a relatively angular adjustment, parts being shown in vertical axial section, and other parts broken away. Fig. 2 is a similar elevation of said elements, but showing the elements as separated and placed in alignment vertically. Fig. 3 is a top plan of the elements shown in said Fig. 1.

The street signs 1 and 7 are alike in body shape but may be made of other shapes than that shown, but in practice the uppermost sign 1 differs from the sign 7 thereunder in not having a cylindrical boss 8 on top, but may have instead any ornamental finial as shown in Fig. 1, at 2.

Each sign has a medial depending and integral boss as at 3 or 11 having an axial downwardly opening cylindrical socket 10 or 15, to receive in the former case an annularly grooved cylindrical boss 8 and in the latter case a like boss 12, the former boss 3 being integral with an upper sign 1 and the boss 12 being integral with a socket-member 16 below the sign 7.

Each socket part 3 and 11 has interiorly threaded radial holes placed ninety degrees apart circumferentially to receive set-screws 5 and 6 whose inner ends engage the annual grooves 9 and 13 respectively in both bosses 8 and 12 which fit said sockets rotatably. It will be seen that the sign 1 may be thus se-

cured together to prevent longitudinal displacement of one sign from the other, and that the set-screws being positioned at ninety degrees apart circumferentially, the upper sign cannot tilt in any direction on the other if slightly loosened. The annular groove in each case permits unlimited angular adjustments of one sign upon the other circumferentially and rotationally.

To support the lowermost sign 7, as above stated, its depending socket 11 is mounted upon a similar boss 12, and the boss 12 is projected upwardly from a wider downwardly opening socket-member 16 whose cylindrical hollow may fit over the cylindrical upper end of a supporting tube 17, and be secured thereto by means of one or more set-screws 18.

These signs are preferably double-faced to be seen from the street or the side-walk. The set-screws indicated by the numeral 14 are set in the same angular relation to each other in the socket-member 11, as above described with the set-screws 5 and 6 in the socket-member 3.

Having described my invention, what I claim as new, and desire to secure by Letters Patent, is:

In combination, street signs superposed and separately connected for desired angular relations, the upper sign having an imperforate integral depending socket projection having interiorly threaded holes at a radial angle from each other, the lower sign having an upwardly directed boss inserted in and to fit the said socket projection and having an annular groove alined with said threaded holes, set-screws mounted in said holes to terminally engage said groove, and the lower sign having a flat top annular part around the base of said upward projection upon whose top the lower rim of said socket projection is sealingly seated, whereby the upper sign may be rotated upon said annular part and secured at a desired angle upon said lower sign with its joint connection to the lower sign sealed against entrance of moisture or other elements.

In testimony whereof I affix my signature.

WALTER K. VOORHEES.
